[57] ABSTRACT

Greeting card display device that simulates Christmas tree when extended, and can be folded generally flat for storage. Device has crown portion having hinged card holders extending radially therefrom, pockets on card holders to accept cards for display. Cylindrical trunk portion has upper end with axial slots to accept card holders, and lower end with axial slots to accept leg portions. Card holders are hinged together by staggered integral hinges or are secured together by spring clip passing through card holder slots in register with each other. Leg portions are flat sheet members with compatible slots, or bent wire members having fingers to grip crown portion and legs to contact ground.

1
GREETING CARD DISPLAY DEVICE

BACKGROUND OF THE INVENTION

1. Field of the Invention

The invention relates to a display device, particularly adapted for but not limited to displaying Christmas cards.

2. Prior Art

A common problem associated with the Christmas season is in displaying Christmas cards in the home. Most cards are designed to stand upright on horizontal surfaces, but such an arrangement involves much work in arranging cards, for instance after household cleaning, or when the cards have fallen over after being disturbed, for example by a draft.

Christmas card display devices are known, such as those shown in U.S. Pat. No. 2,447,856 issued to Hazelton in 1948 and U.S. Pat. No. 2,865,122 issued to Clawson in 1958. Such devices function adequately, but cards displayed thereon cannot be read easily, and often assume an untidy display. Also such devices do not fold into a small storage area and thus are inconvenient for storage during the remainder of the year.

SUMMARY OF THE INVENTION

The invention reduces difficulties of the prior art by providing a Christmas card display device which holds the cards neatly in rows when assembled, thus facilitating the reading of the cards, and one which can be assembled and disassembled within a few minutes and when disassembled can be folded easily and assumes a thin flat shape.

One embodiment of the invention includes a crown portion having a plurality of generally triangular shaped planar card holders having pockets to accept cards. Each holder extends radially in a respective vertical plane from an inner portion thereof adjacent a central axis of the device, to a downwardly and outwardly sloping outer portion. Each card holder is inclined at an angle to adjacent card holders to form the crown portion which simulates a crown portion of a tree. The card holders are secured at the central axis by staggered integral hinges or by a spring clip passing through slots of the inner portions in register with each other. A generally cylindrical trunk portion has a series of peripherally spaced axial slots at an upper end thereof, each slot accepting a respective card holder. The trunk portion has four peripherally spaced axial slots to accept leg portions, each leg portion having a pair of opposite leg elements which extend radially within vertical planes from the trunk portion and support the device generally vertically.

A detailed disclosure following, related to drawings, described embodiments of the invention, which invention is capable of expression in structure other than that particularly described and illustrated.

DESCRIPTION OF THE DRAWINGS

FIG. 1 is a perspective of one embodiment of a display device according to the invention,

FIG. 2 is a detailed perspective showing hinge means and card holding means of the invention,

FIG. 3 is a simplified fragmented section in a horizontal plane through the device, some portions being omitted,

2

FIG. 4 is a fragmented elevation of a portion of a hinge,

FIG. 5 is a perspective of a trunk portion of the device of FIG. 1,

5 FIG. 6 is a side elevation of a leg portion of the device of FIG. 1,

FIG. 7 is a fragmented section on a pocket of the device,

10 FIG. 8 is a simplified fragmented section in a horizontal plan through an alternative crown portion, some portions being omitted,

FIG. 9 is a fragmented section in a vertical plane on a central axis of the portion of FIG. 8,

15 FIG. 10 is a side elevation of a leg element of an alternative trunk portion,

FIG. 11 is a section in a vertical plane on the alternative trunk portion, showing one leg element fitted.

DETAILED DISCLOSURE

FIGS. 1, 2 AND 3

With reference to FIG. 1, a greeting card display device 10 according to the invention has a crown portion 12 having a generally vertical central axis 13, and a trunk portion 14 having a central axis 15, the axes being aligned. The crown portion has a plurality of generally triangular-shaped planar card holders, designated 17 through 22 in FIG. 3. The card holder 17 extends radially in a vertical plane from an inner portion 24 to a downwardly and outwardly extending outer portion 26, outer edges of which are shaped so as to produce an outline resembling a silhouette of a Christmas tree. The remaining holders similarly extend in respective vertical plane, each card holder being inclined at an angle to adjacent card holders, a typical angle 28 between the holders 17 and 18 being about 60°, as shown in FIG. 3. Clearly the angle is dependent on the number of card holders, which can be varied, but six card holders has been found to be suitable so that the crown portion simulates a tree when viewed horizontally from any direction.

As also shown in FIG. 2, each card holder has a plurality of pockets provided on each face thereof, typical pockets 30 being shown on both faces of the card holder 18. Similar pockets 32 are shown on an opposed face of the card holder 19, the pockets 30 being staggered relative to the pockets 32 as shown. When the crown portion is folded for storage there is negligible interference between staggered pockets, thus permitting relatively compact folding of the crown portion. The pockets and folding are described in greater detail with reference to FIG. 7.

As shown in FIG. 1, a sector portion 34 has a pair of edges 36 and 37 inclined at an angle equal to the angle 28, the edges diverging from a sector apex adjacent the central axis of the crown portion. The edge 36 is hinged to the card holder 18 and the opposite edge 37 is in contact with the adjacent card holder 17 so that the sector portion spaces the card holders apart, restricting the card holders against relative hinging. Similar sector portions can be provided between adjacent remaining panels, the sector portions being folded flat against a respective card holder for storage.

With reference to FIG. 3 only, the crown portion 12 includes first, second and third crown panels 39, 40 and 41, each panel having two integral card holders. The second panel 40 is planar and is sandwiched between the first and third panels, the three panels being se-

cured together at central portions thereof. The first and third panels are folded along the central portions so that the card holders of each panel are inclined to each other at the angle 28, which angle, as aforesaid, is approximately 60°. The first and third panels are hinged to the second panel, a suitable hinge 44 for the panel 41 only being described with reference to FIG. 4.

FIG. 4

The hinge 44 is spaced symmetrically about the axis 13 and has two parallel rows of spaced longitudinal slits, namely slits 51 and 52 of row 54 and slits 55 and 56 of row 57. The slits are spaced equally from the axis 13 and are staggered relative to each other, a slit in one row being connected to a slit in the opposite row by a transverse slit, which slit is bisected by the axis 13. Thus adjacent ends of the slits 51 and 52 are joined to the slit 55 by a pair of parallel transverse slits 59 and 60. The slits form integral staggered hinged flaps extending outwards from inner portions of each card holder, two such adjacent flaps 62 and 63 being shown. The flaps are secured to the second panel by a plurality of staples 65, or joined by other means as required. The rows of slits are spaced a few inches from the upper and lower ends of the crown panel and the panel is folded along the centre portion adjacent the ends to provide simple hinging at opposite ends of each card holder.

FIGS. 5 and 6

Referring to FIG. 5, the trunk portion 14 is a generally cylindrical tube having upper and lower ends 71 and 72, the lower end being adjacent a surface supporting the device, the tube having a wall thickness 73 as shown. The upper end has a series of peripherally spaced upper axial slots designated 75 through 80, one slot being provided for each card holder. When the central axes of the trunk and crown portions are aligned, each slot accepts a respective card holder to a depth of a few inches, thus locating the crown portion relative to the trunk portion. The lower end of the trunk has four peripherally spaced axial slots, positions of two slots 82 and 83 only being shown. Four leg elements 85 through 88 extend radially from the trunk portion, adjacent leg elements being inclined equally to each other to produce a stable stand to support the device on the supporting surface and to maintain the device generally vertical.

As shown more clearly in FIG. 6 a leg portion 91 has the two leg elements 85 and 87 extending therefrom, and a similar, but not identical, leg portion 92 (FIG. 5 only) has the leg elements 86 and 88. The leg portion 91 is a plane elongated sheet member having a thickness sufficient to be accepted in the lower axial slots of the trunk portion, and has a lower edge 94 to contact the supporting surface (not shown). An upper edge 96 of the sheet member has a pair of parallel transverse slots 98 and 99 having sufficient width to accept the wall thickness of the trunk portion, the transverse slots being spaced at a diameter of the trunk portion. Thus when the transverse slots 98 and 99 accept the trunk portion, the leg portion extends diametrically across the trunk member as shown in FIG. 5, and in broken outline in FIG. 6 where diametrically opposed portions of the walls of the trunk portion are shown in broken outline. Lengths of the lower axial slots in the trunk member and the corresponding transverse slots of the leg portions are selected to be mutually compatible. As

shown, the length of one lower axial slot equals the length of one transverse slot, which length equals one-half of spacing 101 between the edges 94 and 96 of the sheet member. Other compatible slot lengths can be selected so that the lower edges of the leg portions and the trunk member simultaneously contact the supporting surface. An upwards facing central transverse slot 103 between the parallel transverse slots 98 and 99 is complementary to a corresponding downwards facing central transverse slot (not shown) in the leg portion 92, position of the corresponding slot relative to the leg portion 91 being shown in broken outline and designated 105. The central transverse slots also have compatible slot lengths approximately equal to one-half of the spacing 101, so that when the leg portions fit together the central transverse slots engage adjacent portions of the corresponding leg portions and the lower edges of the leg portions are co-planar.

FIG. 7

One of the pockets 30 on the card holder 18 has an outer wall member 113 spaced from an inner wall 115 of the holder 18 by a spacer 117, the spacer having a thickness greater than maximum thickness of a card 118 (broken outline) retained in the pocket between the member 113 and the wall 115. Other means of retaining cards on the card holders are known, and for convenience, are positioned so that pockets on opposed sides of adjacent card holders are staggered to permit relatively flat folding of the crown portion, as previously described.

OPERATION

The display device 10 is assembled by first unfolding the card holders from a folded condition in which the card holders are relatively parallel (not shown) to an extended position as shown in FIG. 1, with sector portions extended between adjacent corner portions if required. The leg portions 91 and 92 are fitted together so as to be mutually perpendicular, the portions being located by respective central transverse slots. The trunk portion is then fitted over the crossed leg portions, the lower axial slots of the trunk portion being accepted in the spaced parallel slots of the leg portions so that the lower end of the trunk portion and the lower edges of the leg portions are coplanar. The axes of the crown portion and trunk portions are then aligned and card holders of the crown portion are inserted in slots of the upper end of the trunk portion until lower edges of the card holders bottom in the upper axial slots of the trunk portion.

Cards inserted in the pockets face outwards and can be easily removed and read, adjacent cards touching but not obstructing each other. A four foot high device provided with six card holders, each holder having six pockets on each side, can display over one hundred average cards without material obstruction and in a pleasing and orderly arrangement.

ALTERNATIVES AND EQUIVALENTS

FIGS. 8 AND 9

An alternative crown portion 121 has first, second and third crown panels 123, 124 and 125, each panel having two integral card holders similarly to the panels 39, 40 and 41 of FIG. 1. The second panel is planar and sandwiched between the first and third panels, the three panels being secured together by first and second

spring clips, the clip 127 only to be described. The clip 127 has two spaced fingers 129 and 130, the fingers being joined together by a U-shaped member 132 and are spaced sufficiently so as to clamp therebetween central portions of the three card panels. The panel 123 has an elongated slot 134 positioned about mid-way between an apex and a lower end of the crown portion and adjacent the central portion thereof. The crown panels 124 and 125 have similar slots, each slot being positioned relative to the panel so as to be in register with corresponding slots in the adjacent panels when the crown portion is assembled, as shown in FIG. 9. The slots have a length sufficient to permit the first clip to pass through the elongated vertical slots of the panels when in register so that, when the three panels are clamped together, the clip 127 assumes a position as shown in FIG. 9. Lower end of the clip 127 has a tang 136 which facilitates fitting the clip. The second spring clip (not shown) is generally similar to the first clip and is fitted to the apex of the crown portion so as to clamp together the panels at the apex. The lower end of the crown is retained in an alternative trunk portion as will be described with reference to FIGS. 10 and 11.

FIGS. 10 and 11

Referring to FIG. 11, an alternative trunk portion 140 has a central axis 142 and upper and lower ends 143 and 144. The upper end has a series of upper axial slots spaced peripherally therearound, two slots 146 and 147 only being shown, the slots accepting respective card holders similar to the slots 75 through 80 of FIG. 5. The lower end has four peripherally spaced lower axial slots, three such slots 149, 150 and 151 being shown. A leg portion 154 is fitted inside the trunk portion so that leg elements 156 and 157 thereof extend through the slots 149 and 151 of the trunk as shown. Other ends of the leg elements are in contact with a supporting surface, shown as a broken line 160, which is also in contact with the lower end 144 of the trunk portion.

With reference to FIG. 10 the leg portion 154 has a pair of spaced fingers 162 and 163, the fingers adapted to grip a lower portion of the card holders (not shown) therebetween. The portion 154 has a diametrical shoulder 165 having outer portions and a midpoint, the fingers 162 and 163 extending upwards from the midpoint. Axial members 167 and 168 extend downwards from the outer portions of the shoulder to lower ends, the axial members being parallel and spaced apart a spacing 169, the lower ends being spaced from the shoulder portion by a distance 170 to be described. The leg elements 156 and 157 extend outwards from the lower ends of the axial members, to ends in contact with the supporting surface 160.

With reference to FIG. 11 the trunk portion 140 has a bore having a sidewall 172 having a recessed portion 173. The recessed portion extends upwards from an upper end of the lower axial slots a predetermined distance to a shoulder 174, which distance defines axial length 175 of the recessed portion, and is equal to the distance 170 of FIG. 10, i.e. equal to length of the axial members. The recessed portion has a diameter 176 equal to the spacing 169 between outer portions of the axial members 167 and 168 of FIG. 10. The leg portion 154 is fitted within the trunk portion 140 by inserting the fingers 162 and 163 through the lower end of the trunk portion, the leg elements 156 and 157 being ac-

cepted by slots 149 and 151 respectively. The axial members 167 and 168 pass along the bore until slipping into the recessed portion 173 as shown. Difference in diameter of the bore sidewall 172 and the diameter 176 provides positive location for the leg portion. When the leg portion is fitted in the base, the spaced fingers 162 and 163 can be sprung apart sufficiently to clamp therebetween the card holders at the base of the crown portion. A similar leg portion (not shown) is similarly inserted within the bore, at 90° to the portion 154, spaced fingers of the similar leg portion straddling the spaced fingers 162 and 163. Thus the four spaced fingers of the two leg portions extend between four pairs of the six card holders of the crown portion. Good results have been obtained using leg portions of three-sixteenths of an inch mild steel rod or similar stiff wire. When fitted, the lower end 144 of the trunk portion and the four ends of the leg elements are coplanar, thus providing a stable stand for maintaining the device generally vertical.

The alternative crown portion 121 is described for use with the alternative trunk portion 140. Clearly the crown portion 12 of FIG. 1 can be used with the trunk portion 140 and similarly, the crown portion 121 can be used with the trunk portion 14 of FIG. 1.

I claim:

1. A greeting card display device having:

- a. a crown portion having a generally vertical central axis and a plurality of generally triangular shaped, planar card holders having pockets to accept cards, each holder extending radially in a respective vertical plane from an inner portion thereof adjacent the central axis to a downwardly and outwardly extending sloping outer portion, each card holder being inclined at an angle to adjacent card holders, the holders being secured together at the central axis to simulate a crown of a tree,
- b. a generally cylindrical trunk portion having a central axis and upper and lower ends, the upper end having a series of peripherally spaced upper axial slots, each slot accepting a respective card holder when the central axes of the trunk and the crown portion are aligned, the lower end of the trunk portion having four peripherally spaced lower axial slots,
- c. a pair of leg portions, each leg portion being within a vertical plane and having a pair of opposite leg elements, each leg portion having a thickness sufficient to be accepted in the lower axial slots of the trunk portion so that when the device is assembled with the leg portions retained in the trunk portion, four leg elements extend radially from the trunk portion with adjacent leg elements being inclined equally to each other to produce a stable stand for supporting the device on a supporting surface to maintain the device generally vertical.

2. A greeting card display device as claimed in claim 1 in which the crown portion includes:

- i. first, second and third crown panels, each panel having two integral card holders, the second panel being planar and sandwiched between the first and third panels, the three panels being secured together at central portions thereof, the first and third panels being folded along the central portion so that the card holders of each panel are inclined to each other, so that when the crown portion is as-

sembled a particular card holder is inclined at approximately 60° to adjacent card holders.

3. A greeting card display device as claimed in claim 2 in which:

i. the first and third panels are hinged to the second panel. 5

4. A greeting card display device as claimed in claim 3 in which:

i. the central portions of the first and third panels have two rows of spaced parallel longitudinal slits, 10 the slits being staggered, an end of a slit in one row being joined by a transverse slit to an end of an adjacent slit in the opposite row, to form integral staggered hinged flaps extending outwards from inner portions of each card holder, the flaps being secured to the second panel adjacent the central portion thereof. 15

5. A greeting card display device as claimed in claim 2 in which the crown panels are secured together by first and second spring clips, wherein:

i. the first spring clip has two spaced fingers, the fingers being spaced so as to clamp therebetween the central portions of the three panels, 20

ii. a second spring clip generally similar to the first clip and fitted to an apex of the crown portion so as to clamp together upper ends of the crown panels, 25

iii. each crown panel has an elongated vertical slot adjacent the central portion thereof, the slot being positioned so as to be in register with corresponding slots in adjacent panels when the crown portion is assembled, each slot having a length sufficient to permit the first clip to pass through the three elongated vertical slots of the panels when in register, so as to secure the panels together at the central 30 portions thereof.

6. A greeting card display device as claimed in claim 1 in which

i. the trunk portion is tubular and has a wall having a thickness, and each leg portion has: 40

ii. a plane elongated sheet member having a lower edge to contact the supporting surface, and an upper edge having a pair of parallel transverse slots having sufficient width to accept walls of the trunk portion, the transverse slots being spaced at a diameter of the trunk portion so that the lower slots of the trunk portion accept the transverse slots and the sheet member extends diametrically across the trunk member, 45

iii. a central transverse slot between the pair of parallel transverse slots, which slot has a length compatible with a corresponding transverse slot in the corresponding leg portion, and the slot has a width sufficient to accept thickness of the corresponding leg portion, so that when the leg portions are fitted together, the central transverse slots engage adjacent 50

portions of the corresponding leg portions, and the lower edges of the leg portions are coplanar.

7. A greeting card display device as claimed in claim 1 in which:

i. the trunk portion has a bore, the bore having a recessed portion extending upwards from an upper end of the lower axial slots a predetermined distance to a shoulder, which distance defines axial length of the recessed portion,

ii. each leg portion includes; a pair of spaced fingers at an upper end, the fingers adapted to grip a lower portion of the card holders therebetween, a diametrical shoulder having outer portions, the fingers extending upwards from a midpoint of the diametrical shoulder; spaced parallel axial members extending downwards from the outer portions of the shoulder, the axial members having lower ends spaced from the shoulder portion a distance equal to the axial length of the recessed portion; leg elements extending outwards from the lower end of the axial members, so that when the leg portions are mutually perpendicular to each other and are fitted inside the trunk portion, the leg elements are adjacent upper ends of, and extend through, the lower axial slots of the trunk portion, the axial members extend within the recessed portion of the bore, the diametrical shoulder portion is adjacent the shoulder of the recessed portion, and the fingers extend from the upper end of the trunk portion to accept the crown portion.

8. A greeting card display device as claimed in claim 7 in which:

i. the leg elements are made from stiff wire.

9. A greeting card display device as claimed in claim 1 further including:

d. a sector portion having a pair of edges inclined at an angle equal to the angle between adjacent card holders, the edges diverging from a sector apex adjacent the central axis of the crown portion, one edge being hinged to one card holder, the opposite edge being in contact with the adjacent card holder, so that the sector portion spaces adjacent panels apart so that the panels are restricted against relative hinging.

10. A greeting card display device as claimed in claim 1 in which:

i. the pockets on one side of the card holder are staggered relative to pockets on an opposed side of an adjacent holder, so that when the crown portion is folded for storage and adjacent card holders contact each other, there is negligible interference between pockets on opposed sides of card holders, thus producing a relatively compactly folded crown portion.
